UNITED STATES PATENT OFFICE.

JOHANNES S. VELTHOEN, OF ROTTERDAM, NETHERLANDS, ASSIGNOR TO U. S. SLICING MACHINE COMPANY, OF LA PORTE, INDIANA, A CORPORATION OF INDIANA.

SLICING MACHINE.

Application filed November 14, 1927, Serial No. 232,955, and in Germany January 15, 1927.

This invention relates to machines for slicing meat and other commodities, and has for one of its objects the provision of means for preventing improper or accidental operation of the machine.

A further object is to provide a slicing machine of improved construction and operation.

The invention is exemplified in the combination and arrangement of parts shown in the accompanying drawing and described in the following specification, and it is more particularly pointed out in the appended claims.

15 In the drawings—

Fig. 1 is an elevation of a slicing machine showing one embodiment of the present invention applied thereto; and

20 Fig. 2 is a vertical section showing the lock for the reciprocating table on a larger scale than that of Fig. 1.

In many forms of slicing machines having rotary circular knives, the operating mechanism for the reciprocating carriage and the 25 mechanism for driving the knife are connected so that reciprocation of the carriage will produce rotation of the knife. Where this is the case, accidental movement of the carriage produces rotation of the knife, 30 which being unexpected, may result in serious injury to the persons manipulating the machine.

The present invention provides means for preventing reciprocation of the carriage, except when the operator grasps the proper 35 device for intentional operation of the machine.

In the drawing, the numeral 10 designates the base of a slicing machine having a rotary 40 circular slicing knife 11 mounted thereon. The form of the machine shown is one in which the machine is operated by pressure exerted directly on the reciprocating carriage. This carriage is shown at 12 and is 45 provided with the usual feed table 13 having a clamp 14 for holding the meat or other material to be sliced, in position. Projecting from the reciprocating carriage at the operator's side of the machine, are spaced brackets 50 15 which support a handle bar 16. The detent 17 is pivotally mounted at 18 on one of the brackets 15 and is provided with a release bar 19 arranged parallel with the operating handle 16 and at the inner side there-

of. A spring 20 normally holds the detent 17 in position to engage spaced notches 21 formed in the upper face of the base 10. A plurality of notches 21 are provided so that the reciprocating table may be held against movement at various positions along its path of travel.

To operate the machine, the attendant grasps both the handle 16 and the bar 19 in his hand and by pressing the two together, the bar 19 is moved against the handle 16 and the detent 17 is released. The table may then be reciprocated in the usual way. If an effort is made to reciprocate the table by grasping any other portion thereof than the handle 16 and bar 19, the detent 17 will prevent movement of the table. This will occur irrespective of the position of the reciprocating table upon its support for the reason that notches are distributed along the path of movement of the table so that only a slight movement from any position will be permitted before the detent will be brought into registration with one of the notches and lock the table against further movement.

It will be seen that the handle 16 is disposed at the operator's side of the slicing machine so that it is necessary for the operator to take his proper position relative to the machine in order to release the detent 17. This requires him to move away from the knife and removes the temptation for the operator to grasp one of the clamping uprights or other parts of the reciprocating table to adjust the position of the table if he happens to be at the side of the machine adjacent the knife. It will also be noted that the release bar 19 is positioned on the inner side of the handle 16 so that the handle 16 acts as a guard for preventing accidental contact with the release bar for the detent.

I claim:—

1. The combination with a slicing machine having a rotary slicing knife and a reciprocating feed table, of means for holding said feed table against reciprocation, and means for releasing said holding means when said slicing machine is properly operated.

2. The combination with a slicing machine having a rotary slicing knife, of a handle member for operating said slicing machine, means for preventing accidental

operation of said slicing machine, and means associated with said handle for releasing said operation preventing means.

3. The combination with a slicing machine having a slicing knife and a reciprocating support for material to be sliced, of a detent for preventing accidental reciprocation of said support, a handle for operating said slicing machine, and means associated with said handle for releasing said detent.

4. The combination with a slicing machine having a reciprocating support, of a handle carried by said support, a detent for preventing reciprocation of said support, and means associated with said handle for releasing said detent.

5. The combination with a slicing machine, of a lock for preventing accidental operation of said slicing machine, a handle for operating said slicing machine, and means associated with said handle for releasing said lock.

6. The combination with a slicing machine, of a lock for preventing operation of said slicing machine, a handle arranged at the operator's side of said slicing machine for operating said slicing machine, and means associated with said handle for releasing said lock, said handle being arranged in position to serve as a guard against accidental engagement with said lock.

7. The combination with a slicing machine having a reciprocating carriage, of a detent pivotally mounted on said carriage and arranged to engage the carriage support, said support having spaced stops thereon for co-

operating with said detent to prevent movement of said carriage.

8. The combination with a slicing machine having a supporting base, a rotary knife mounted on said base and a reciprocating carriage arranged to travel along said base, of a detent pivotally mounted on said carriage, stops on said base for engaging said detent, a handle for operating said slicing machine, and means associated with said handle for releasing said detent.

9. The combination with a slicing machine having a supporting base, a rotary knife mounted on said base and a carriage arranged to reciprocate on said base, of a detent pivotally mounted on said carriage in position to engage said base, stops on said base for engaging said detent to hold said carriage against movement, a handle bar secured to said carriage at the operator's side of the slicing machine, and a release bar connected to said detent and disposed adjacent said handle bar and at the inner side thereof.

10. The combination with a slicing machine having a rotary knife and a reciprocating table, of a handle for reciprocating said table, a detent normally urged into operative position to hold said table against movement, said detent having a portion thereof adjacent said handle for moving said detent into inoperative position when said portion is moved toward said handle.

In testimony whereof I have signed my name to this specification on this 27th day of October, A. D. 1927.

JOHANNES S. VELTHOEN.
